US00D860969S

(12) **United States Design Patent** (10) Patent No.: **US D860,969 S**
Brunner et al. (45) Date of Patent: ** Sep. 24, 2019

(54) **HEADSET**(71) Applicant: **Apple Inc.**, Cupertino, CA (US)(72) Inventors: **Robert D. Brunner**, San Francisco, CA (US); **Christopher Kuh**, San Francisco, CA (US)(73) Assignee: **Apple Inc.**, Cupertino, CA (US)(**) Term: **15 Years**(21) Appl. No.: **29/642,633**(22) Filed: **Mar. 30, 2018**

CLAIM

The ornamental design for a headset, as shown and described.

DESCRIPTION

FIG. 1 is a front perspective view of a headset showing the claimed design;

FIG. 2 is a rear view thereof;

FIG. 3 is a bottom view thereof;

FIG. 4 is a front view thereof;

FIG. 5 is a right side view thereof;

FIG. 6 is a left side view thereof; and,

FIG. 7 is a top view thereof.

The broken lines in the figures show portions of the headset that form no part of the claimed design.
